CARBON CHANGE SIGNALING DEVICE FOR AN AUTOGRAPHIC REGISTER

Louis Jensen, Chicago, Ill., assignor to Uarco, Incorporated, a corporation of Illinois

Application July 3, 1953, Serial No. 366,031

5 Claims. (Cl. 282—1)

This invention relates to a signaling device for an autographic register, and more particularly to an apparatus to inform a person operating the register of the need for advancing the carbon strips used in the register.

Autographic registers commonly use zigzag folded continuous form stationary. Several strips of forms are superposed, and separate carbon strips are transversely interleaved with the strips over the platen to obtain duplicate filled forms. The present invention is a type of counting device which indicates to the user of the register when a portion of the carbon strips have been used a predetermined number of times. With the present device guesswork is eliminated, the economical life of the carbon strip is utilized, and copies of the original form are always legible.

The primary object of this invention is to provide a mechanism for visibly indicating the number of times a particular group of carbon strips have been used in conjunction with the form-feeding operation of an autographic register.

Another object is to provide an indicating mechanism which can be set to respond visibly to a predetermined number of form-feeding operations of an autographic register.

A further object is to provide a mechanism having a visible indicator placed adjacent the actuating handle of an autographic register form-feeding mechanism to make the operator aware that the carbon should be changed.

The invention is illustrated in a preferred embodiment in the accompanying drawings, in which:

Fig. 1 is a fragmentary plan view of an autographic register partly in section and partly broken away to illustrate the invention;

Fig. 2, a fragmentary vertical sectional view taken as indicated on line 2—2 of Fig. 1;

Fig. 3, a fragmentary plan view of the flag member;

Fig. 4, a vertical sectional view similar to Fig. 2, showing the flag member in released position;

Fig. 5, a plan view of the cam member and an adjacent gear removed from the autographic register;

Fig. 6, a fragmentary vertical sectional view taken as indicated on line 6—6 of Fig. 4;

Fig. 7, a fragmentary vertical sectional view taken as indicated on line 7—7 of Fig. 4;

Fig. 8, a plan view of the wheel which sets the frequency of operation of the indicating mechanism; and

Fig. 9, a plan view of the toothed gear in the ratchet mechanism.

In the embodiment illustrated, an autographic register has a platen 10 over which the continuous forms of stationery are advanced, and which is mounted upon a housing 11. An operating handle 12 is connected to a shaft 13 to turn gears 14 and 15 and drive the form-feeding mechanism of the register. Gears 14 and 15 also rotate the cam members 16 upon the shaft 17 through a pair of gears 18 and 19 to provide the drive

2

means for the carbon change signaling device. The signaling device is mounted upon a base member 11a which is generally secured to the housing within the record compartment of the register.

5 A flag member 20, mounted within the housing 11 adjacent the handle 12, has a pair of longitudinal slots 21 and 22 operating on a pair of guide screws 23 and 24 to limit and to guide the movement of the flag member. A notch 25 is provided along one longitudinal edge 10 of the flag member to engage a releasable latch means so that the flag may be held within the register. Upon withdrawal of the latch means from the notch 25, a spring 26 pulls the flag upwardly through a slot 27 in the housing 11 to indicate to the operator that the carbon sheets 15 need changing.

The latch means which holds the flag in concealed position within the register includes a bell-crank lever 28 having a notch engaging portion 29 and a pivot arm 30. The lever is pivoted upon a cap screw 31 and normally urged toward notch engaging position by the spring 20 32. The latch means becomes disengaged from the flag member 20 when the arm 30 is moved upwardly to pivot the portion 29 out of the notch 25.

A latch release mechanism, provided to disengage the 25 latch means performs its function in accordance with a predetermined setting of the release mechanism. In this particular embodiment the release mechanism is mounted on a fixed shaft 33. It includes a toothed wheel 34 and an integral sleeve 35, both freely pivoted on the 30 shaft 33. An abutting sleeve 36 has detents 37 and 38 on opposite faces of its flanged end 39, and is held in fixed position upon the threaded end of the shaft 33 by a nut 40. A tensioned coiled spring 41 embraces the sleeve 35 and is anchored by the detent 37 and cap screw 35 42 to urge the toothed wheel 34 in a clockwise direction, as viewed in Fig. 2.

The rotary movement of the toothed wheel 34 in clockwise direction is always limited by engagement between a stud 43 on the toothed wheel 34 and a stud 44 on a 40 floating wheel 45. The floating wheel 45 is mounted upon the sleeve 36 and is yieldingly held adjacent the flanged end 39 by a coiled spring 46 so that any one of the apertures 47 in the wheel 45 can be placed about the detent 38 to adjust the position of the stud 44.

45 The toothed wheel is given intermittent rotary motion by engagement of an advancing pawl 48 with the teeth of the wheel. A pawl advancing portion 49 is pivoted about the shaft 33 and has a flanged end 50 which has a notch 51 adapted to engage a reciprocating drive 50 means to be described later. The advancing pawl 48 is pivoted to the portion 49 by a cap screw 52, and is yieldingly held in engagement with the toothed wheel by the spring 53. Since the advancing pawl is attached to the portion 49, the pawl forces the toothed wheel in 55 a counter-clockwise direction, as viewed in Fig. 2, when the pawl advancing portion is driven by the reciprocating drive means. The advancing pawl 48 and the portion 49 are returned for the next stroke of the drive means by the spring 54.

60 A braking pawl 55, pivoted upon the cap screw 56, is yieldingly held in engagement with the toothed wheel by the spring 57. In operation, the toothed wheel is advanced sufficiently far to insure engagement between the braking pawl 55 and the toothed wheel before the advancing pawl 48 is withdrawn by the spring 54.

65 The drive means for the indicating mechanism includes a rotary cam member 16 mounted upon the shaft 17. The motion of the cam is transmitted by a follower 59 which engages the notch 51 in the flanged end 50. The follower is floatingly mounted upon the support member 59 by a pair of guide screws 60 operating in a longitudinal slot 61 in the follower.

The gearing of the drive means is arranged so that the cam member 16 makes one complete rotation for every two operations of the handle 12. Thus it is seen that the follower 59 engages the notch 51 in the flanged end 50 every other turn of the operating handle 12, and the toothed wheel is advanced one notch by the advancing pawl 45 every other turn of the operating handle.

After each advancement of the follower, it is returned only part way to its initial position by the spring 54. A spring 62 which pulls a crank shaft 63, mounting a folding blade (not shown), against the shoulder 64 of the follower completes the movement of the follower to its initial position near the cam 16. The alternating action of the follower also operates the folding blade to deposit record stationery strips in proper folded relation in opposite ends of the record compartment of the register.

The latch releasing operation is similar to the tripping of a trigger. The stud 43 advances in a counter-clockwise direction, as shown in Fig. 2, each time the advancing pawl turns the toothed wheel. Ultimately the stud 43 advances to a position adjacent the end of the bell-crank lever pivot arm 30. The next advance of the toothed wheel causes the stud 43 to trip the lever arm 30 disengaging the notch engaging portion 29 of the bell-crank lever 28 from the notch 25 and allowing the flag member 20 to be sprung upwardly by the spring 26.

When the flag member is disengaged, the advancing and braking pawls are likewise disengaged from the toothed wheel to allow the wheel to be turned by the coil spring 41, returning the stud 43 to its initial position in contact with the stud 44 of the floating wheel 45. When the flag member is released, the braking pawl is disengaged from the toothed wheel by the ledge 65 on the flag member bearing upwardly on an end of the pawl. The advancing pawl is disengaged from the toothed wheel by the upward engagement of a machine screw 66 upon the end of a pivoted lever 67 which raises the advancing pawl from its engaged position.

The indicating mechanism is recocked by once again lowering the flag member within the housing 11, so that the notch engaging portion 29 of the bell-crank lever again recesses in the notch in the flag member. The lowering of the flag member removes the ledge 65 and the machine screw 66 from contact with the advancing and braking pawls so that the two pawls are once again urged into engagement with the toothed wheel by their respective springs. At this point the stud 43 and the toothed wheel are once again in initial position ready to be successively advanced by the advancing pawl 48 toward bell-crank lever arm tripping position.

The foregoing detailed description is given for clearness of understanding only and no unnecessary limitations should be understood therefrom, for some modifications will be obvious to those skilled in the art.

I claim:

1. A carbon change signaling device for an autographic register having a form-feeding mechanism, comprising: a flag member mounted within the register and releasable from a concealed position in the register to signaling position; spring means urging said flag member toward signaling position; a spring loaded trigger mechanism for engaging and releasably holding said flag member in concealed position; a ratchet member having a stud for tripping said trigger mechanism in one position to release the flag member from concealed position; and

drive means actuated by the form-feeding mechanism for advancing the ratchet member step-by-step from an initial position to said one position, whereby the flag will be released after a predetermined number of operations of the form-feeding mechanism.

2. A signaling device as specified in claim 1, in which the ratchet member is normally spring-urged toward the initial position and means are provided movable with the flag member for disengaging the drive means from the ratchet member when the flag member moves to signaling position to permit the ratchet member to return to its initial position.

3. A signaling device as specified in claim 2, in which a second stud is adjustably mounted within the register adjacent the ratchet member and in the path of movement of the first stud on the ratchet member so that the studs are brought into abutting relation when the ratchet member is disengaged from the drive means, said studs in abutment defining the initial position of the ratchet member, the second stud being manually adjustable to vary said initial position.

4. A signalling device as specified in claim 2, in which an advancing pawl is provided for imparting intermittent rotary movement to the ratchet member, a braking pawl is provided to hold the ratchet member in its advanced position, and the means movable with the flag member comprises a pair of shoulders each adapted to contact and disengage a pawl from the ratchet member as the flag member is moved to signaling position.

5. A carbon change signaling device for an autographic register, comprising: a flag member; a guideway mounted within the register to direct said flag member from concealed position to signaling position; spring means yieldably urging said flag member toward its signaling position; a spring loaded trigger mechanism releasably holding said flag member in its concealed position; a ratchet mechanism including a toothed wheel having a stud secured to the wheel for tripping said trigger mechanism to release said flag member, an advancing pawl for intermittent rotary advancement of said wheel, and a braking pawl to hold said wheel in its advanced position; a second spring means yieldable urging said toothed wheel toward its initial position; a drive mechanism including a cam member on the form-feeding mechanism of the register, and a reciprocable cam follower engaging said cam and the advancing pawl of said ratchet mechanism, whereby the stud on said toothed wheel is advanced step-by-step into tripping engagement with said trigger mechanism, permitting the flag member to move to signalling position of the register; and means for manually adjusting the initial position relative to the trigger tripping position, said means including a shaft mounting the toothed wheel; a flanged sleeve fixed to said shaft and having an outwardly extending detent on the flange, a floating wheel on said shaft having a series of apertures each adapted to fit about said detent, and a stop member on said floating wheel for engaging the stud on the toothed wheel to establish the initial position, the position of said stop member being dependent upon the particular aperture fitted about said detent.
